NORMALIZING CIRCUIT

Dwight V. Sinnerger, Chicago, Ill., assignor to
 Johnson Laboratories, Inc., Chicago, Ill., a corporation of Illinois

Application June 17, 1937, Serial No. 148,668

1 Claim. (Cl. 179—171)

This invention relates to improvements in high-frequency amplifying systems, and more particularly to vacuum-tube amplifiers of the type commonly employed in receivers for modulated high-frequency signals. Although applicable to various types of high-frequency amplifiers, the invention is especially useful in amplifiers intended for operation over a limited range of frequencies, as for example the intermediate-frequency amplifier of a radio receiver of the superheterodyne type. Such an amplifier is usually initially adjusted for optimum performance at a single fixed frequency, but is designed to pass a relatively narrow band of frequencies lying on either side 15 of its nominal resonant frequency.

In vacuum-tube amplifiers intended for operation at high frequencies, the electrical characteristics of the vacuum tubes themselves introduce several serious problems which must be solved in 20 the design of a satisfactory multi-stage amplifier. One of these difficulties is the inherent grid-plate capacitance of the vacuum tube. This capacitance permits a certain amount of feedback from the plate circuit to the grid circuit of the vacuum tube, and, in a high-gain amplifier, this feedback 25 may be sufficient to produce instability and oscillation. Although the effective grid-plate capacitance may be reduced substantially by the use of a screen-grid within the vacuum tube itself, in 30 many cases it is sufficient to introduce serious difficulty in the design of a high-gain amplifier.

Another difficulty directly attributable to the electrical characteristics of the vacuum tube itself is that due to the output capacitance of the tube. Especially in the case of vacuum tubes of 35 the type employing a grounded metal outer envelope or shell, the output capacitance is great enough to contribute to the instability and tendency to oscillate of a multi-stage vacuum-tube 40 amplifier, thus seriously limiting the useful gain or amplification which may be realized.

An object of this invention is to provide simple and inexpensive means for substantially eliminating the undesirable effects of vacuum-tube 45 output capacitance in high-gain, multi-stage amplifiers.

Another object of the invention is to provide means for preventing feedback and instability due to the use of a common source of plate potential 50 for the vacuum tubes of a multi-stage amplifier.

An additional object of the invention is to provide means for substantially increasing the stable 55 amplification which may be realized in a multi-stage vacuum-tube amplifier.

Although the arrangements of the invention are applicable to various types of high-frequency vacuum-tube amplifiers, they are especially useful in intermediate-frequency amplifiers which are designed to have a flat-topped, steep-sided 5 selectivity characteristic, since feedback has a marked tendency to alter the symmetry of the amplifier characteristic and thus introduce serious distortion of the modulated high-frequency signal being amplified. It is a further object of 10 the invention, therefore, to provide a high-frequency amplifier which is capable of being adjusted to have a substantially symmetrical selectivity characteristic of a desired form.

The invention will be better understood by reference to the drawing, in which:

Fig. 1 is the schematic wiring diagram of a vacuum-tube amplifier employing the arrangements of the invention; and

Fig. 2 is an equivalent diagram of one portion 20 of the diagram of Fig. 1.

Referring to Fig. 1, vacuum tube 1 is coupled to vacuum tube 2 by means of coupling device 3 to form a vacuum-tube amplifier. It will be understood that either of vacuum tubes 1 and 2 25 may be arranged to function otherwise than as an amplifier. For example, for use in a superheterodyne radio receiver vacuum tube 1 might be employed as the first detector. Dotted capacitors 4 and 5 represent the output capacitances of 30 vacuum tubes 1 and 2, respectively. By-pass capacitor 6 forms a path of relatively low impedance for high-frequency currents in the plate circuit of vacuum tube 1, and the high-frequency currents in the plate circuit of vacuum tube 2 35 pass through capacitor 7. Inductor 8 in the plate circuit of vacuum tube 2 is shunted by adjustable capacitor 9 in series with fixed capacitor 10. Plate potential is supplied to vacuum tube 2 through series resistor 11, which is in shunt with 40 fixed capacitor 10.

Although coupling device 3 is shown to consist of two inductively coupled inductors 12 and 13 which are tuned by adjustable capacitors 14 and 15, respectively, it will be understood that any other 45 suitable coupling means may be employed between vacuum tubes 1 and 2. For example, a coupling device employing three or more resonant circuits may be used if desired without departing from the scope of the invention. The 50 grid-plate capacitance of vacuum tube 2 is represented by dotted capacitor 16.

Although the major portion of the high-frequency current which flows in inductor 12 passes through tuning capacitor 14, some current flows 55

also through by-pass capacitor 6 and output capacitance 4 of vacuum tube 1, which are effectively in series across tuned circuit 12-14. Assuming that capacitor 10 were momentarily short-circuited and capacitor 7 removed, it is evident that a portion of the circulating current of tuned circuit 8-9 would flow through capacitor 6 which is effectively in series with the output capacitance 5 of vacuum tube 2. Such a common path for portions of the high-frequency currents flowing in the plate circuits of two successive amplifying vacuum tubes introduces serious feedback difficulties, with resultant instability and an unsymmetrical selectivity characteristic for the amplifier as a whole.

The invention provides means whereby the coupling which is common to circuits 12-14 and 8-9 may be balanced out. The operation of the arrangement of Fig. 1 may be better understood by reference to Fig. 2, in which like parts are designated by like reference numerals. Capacitors 5, 7, 9 and 10 form the four arms of a capacitance bridge, across one diagonal of which is connected inductor 8 and across the other diagonal of which is connected by-pass capacitor 6. Resistor 11, in shunt with capacitor 10, has no appreciable effect upon the operation of the bridge, but is necessary to provide a direct-current path to the plate of vacuum tube 2. A choke 30 coil may be substituted for resistor 11.

The value of capacitor 5 depends upon the characteristics of vacuum tube 2 and thus is not readily adjustable. Capacitors 9 and 10 in series are in shunt with inductor 8, so that their values cannot be changed without affecting the resonant frequency of the output circuit of vacuum tube 2. In practice, capacitor 10 is fixed at a suitable value and capacitor 9 is adjustable to provide a means for aligning the circuit 8-9 at the desired frequency. Capacitor 7 may be given any desired value in order that the bridge may have the proper adjustment to eliminate the effects of undesired couplings between circuits 12-14 and 8-9, and will require only a slight readjustment 45 of capacitor 7.

In practice, it has been found that the degree of mis-adjustment introduced by vacuum tube replacement or by alignment of tuned circuit 8-9 is not sufficient to introduce serious feedback difficulties in an otherwise properly adjusted system. It is within the scope of the invention, however, to provide means for re-adjusting the bridge if necessary, as for example by making capacitor 7 adjustable.

If the grid-plate capacitance 16 of vacuum tube 2 is assumed to be zero, the only coupling between the output circuit of vacuum tube 1 and the output circuit of vacuum tube 2 is that due to capacitor 6. This coupling may be balanced out by so choosing the value of capacitor 7 that the ratio of capacitors 10 and 7 is equal to the ratio of capacitors 9 and 5. This is the condition which would exist were additional means, not shown, to be employed to balance out the effect of grid-plate capacitance 16. When the bridge is balanced in this case, therefore, there is no common coupling or tendency toward feedback due to by-pass capacitor 6, and the system is stable.

In most cases, however, the grid-plate capaci-

tance 16 of vacuum tube 2 is not neutralized, and thus provides a coupling between circuits 12-14 and 8-9 which either aids or opposes the coupling due to capacitor 6, depending upon the polarity of inductor 13 with respect to that of inductor 12. When the coupling due to capacitance 16 aids that of capacitor 6, the bridge must be unbalanced in the proper sense and degree to nullify the sum of the two couplings. This may be accomplished by so choosing capacitor 7 that the ratio of capacitors 10 and 7 is enough smaller than the ratio of capacitors 9 and 5 to compensate for the combined undesired couplings. The constants given below for an illustrative embodiment of the invention apply to a case of this type.

If the coupling due to grid-plate capacitance 16 opposes but is less than the coupling due to capacitor 6, the bridge must be unbalanced to compensate for the difference between the two couplings. This may be accomplished by so choosing capacitor 7 that the ratio of capacitors 10 and 7 is sufficiently greater than the ratio of capacitors 9 and 5 to compensate for the coupling which remains. If the bridge constants are suitably chosen to meet this condition, the system will be free from instability due to coupling between circuits 12-14 and 8-9.

By way of example of one successful embodiment of the arrangements shown in Fig. 1 of the drawing, the following constants are given for a system designed to operate at a frequency of 460 kilocycles:

Vacuum tubes 1 and 2	----- Type 6K7.	40
Capacitors 4 and 5	----- 12 micromicrofarads.	35
Capacitor 6	----- 0.05 microfarad.	
Capacitor 7	----- 0.005 microfarad.	
Capacitors 9 and 14	----- 104 micromicrofarads (approximate setting).	
Capacitor 10	----- 0.01 microfarad.	
Resistor 11	----- 800 ohms.	
Inductors 8 and 12	----- 1.0 millihenry.	

It will be understood that these are approximate values and that the scope of the invention is in no way limited to embodiments employing the same or even closely similar values. A different operating frequency or the use of different types of vacuum tubes may require changes in some of the constants, and such changes are both contemplated and within the scope of the invention.

Having thus described my invention, what I claim is:

In a high-frequency amplifier, a first vacuum tube having a plate and a plate circuit, said plate circuit including a parallel tuned circuit and a source of plate potential shunted by a capacitor; a second vacuum tube having a plate and a plate circuit, said last-mentioned plate circuit including a parallel tuned circuit comprising an inductor shunted by an adjustable capacitor and a fixed capacitor in series, said fixed capacitor being shunted by a resistor; a connection from the junction of said adjustable capacitor and said fixed capacitor to the positive terminal of said source of plate potential; and a capacitor connected between ground and the junction of said inductor and said resistor.
